FIN FOR A WATER SKI OR SURFBOARD

Robert L. Sackett, 945 Pacific Beach Drive,
San Diego, Calif. 92109

Filed Aug. 8, 1966, Ser. No. 3,384

Term of patent 14 years

(Cl. D71—1)

Fig. 1

Fig. 2

Fig. 3

Fig. 4

FIGURE 1 is a side elevational view of a fin for a water ski or surfboard, showing my new design;

I claim:

The ornamental design for a fin for a water ski or surfboard, as shown and described.
